UNITED STATES PATENT OFFICE.

SHERIDAN A. WALKER, OF NEW YORK, N. Y., ASSIGNOR, BY MESNE ASSIGNMENTS, TO THE CARSON COMPANY, OF CHICAGO, ILLINOIS, A CORPORATION OF ILLINOIS.

ROCKER MECHANISM FOR CAR-SEATS.

1,301,020.

Specification of Letters Patent. Patented Apr. 15, 1919.

Application filed July 9, 1918. Serial No. 244,067.

To all whom it may concern:

Be it known that I, SHERIDAN A. WALKER, a citizen of the United States, residing at New York, in the county of New York and State of New York, have invented certain new and useful Improvements in Rocker Mechanisms for Car-Seats, of which the following is a specification.

The present invention relates to certain mechanism for shifting the angle of the cushion as a car seat back is moved, and which is commonly referred to as the rocker mechanism, and further to the means for supporting this mechanism and the car seat.

15 The object of the invention is to so arrange the rocker mechanism that there will be a retarding or braking action imparted to the back just prior to reaching its limit of movement, so that the back does not settle into its final position with a jolt or jar which would tend to disorganize the mechanism.

20 A further object of the invention is to so construct and arrange the rocker plates and the means for operating the same that a clear space can be left at the side of the car body for the passage of steam pipes.

25 A further object of the invention is to form the rocker plates of a truss formation and have the operating rods therefor and 30 supporting rods therefor pass directly through the plate, thus enabling the plate to be made of a relatively broad and substantial character.

35 A further object of the invention is to utilize a plate of a relatively broad and substantial character and to so support it as to have it spaced a proper distance above the car floor and yet not place the top of the cushion of the seat objectionably high 40 from the floor.

A further object of the invention is to 45 secure the rocker plates in position in a manner so that they cannot be detached from the supporting rods and thus become misplaced or lost.

50 A further object of the invention is to so arrange the rocked plates that they may, if desired, be adjusted on the operating rods and supporting rods so as to be moved to various positions with respect to the aisle or car end of the seat.

The invention further consists in the features of construction and combination of parts hereinafter described and claimed.

55 In the drawings:

Figure 1 is a side elevation of the seat of the present invention.

Fig. 2 is a front view of the aisle end thereof;

Fig. 3 is a view similar to Fig. 1, with the 60 back in reverse position;

Fig. 4 is a detail showing the position of the rocker plate at the commencement of placing the braking or retarding action on the seat back;

Fig. 5 is a plan view showing one of the rocker plates and the connecting and operating rods in operative position thereto; and

Fig. 6 is a detail cross section of the 70 rocker plate.

In the art to which the present invention relates, considerable difficulty exists in reversing the back of the seat, in that the back when it moves to its final reverse position will assume momentum enough to cause it to 75 settle with a jar, jolting the mechanism of the seat, and thus disorganizing and in some instances breaking the same.

Difficulty has also been experienced in 80 properly supporting the seats so as to leave enough clearance between the supporting rods and the floor, which the railroads require to be ten inches, and yet not have the top of the cushion elevated so far above the floor as to make it uncomfortable to sit 85 upon.

Further difficulty exists in that the workmen in repairing or repainting the cars will 90 remove the rocker plates and they thus become lost, and then when an attempt is made to put the car back into service, it has to be laid up in the yards for a considerable length of time awaiting the securance of new rocker plates to replace those that have been lost in the shop.

95 The above difficulties are some of those which the present invention is concerned in overcoming.

Referring now to the drawings, the invention is shown in conjunction with a car 100 seat 7, comprising a back 8 of any suitable style, an arm 9, cushion 10 and pedestal 11. All of the above parts may be of any suitable shape and style of construction.

Extending from the pedestal 11 is a 105 bracket or support 12, to which is secured rods 13. These rods constitute the supporting rods for the car seat, and as shown are secured to the bracket of the pedestal by a strap 14, joined together by a bolt 15. These 110

rods 13 extend across to a wall plate 16, located on the side of the car, and are joined to the wall plate by means of a sleeve or ferrule 17, through which extends a suitable bolt or other locking member 18.

The rods are also joined to the arm 9 of the seat by a sleeve and bolt connection similar to that described above with respect to the wall plate. These rods 13 extend through slots 19 formed in a rocker plate 20, there being one slot located at each end of the plate, and one of the rods extends through each slot. There are two of these plates, one located adjacent the aisle end of the seat and the other adjacent the wall end. They are both exactly alike in construction and a detailed description of one will therefore suffice.

Each of these slots 19 is formed of what may be termed an elongated portion 21, a short or terminal portion 22, and an angularly disposed portion 23. The angularly disposed portion is the connecting part between the elongated portion 21 and short portion 22. The rocker plates are each provided with the usual studs 24, which receive the cushion 10. Each of the plates is further provided with vertical slots 25, through which extend rods 26 constituting the operating rods for the plates, a description of which will be hereinafter given.

From the foregoing, it will be observed that both the operating and supporting rods for the rocker plates extend directly through the plate. The plate itself is of truss formation, as will be seen from Fig. 6, and can thus be made very strong and substantial. By passing the supporting rods 13 directly through the plates, these rods can pass very close to the upper and lower edges of the plate, as will be apparent from Figs. 3 and 4.

Therefore, the lower edge of the cushion, which rests upon the top of the rocker plates, will be brought close down to these supporting rods. The rods can be placed the required ten inches above the floor line, and owing to the cushion resting so close to the rods, the top of the cushion will not be raised so high as to make it uncomfortable to sit in, which is the case in the constructions wherein the rocker plates are placed entirely above the supporting rods and then the cushion on top of the plate.

In the operation of these car seats, wherein the back is swung from one side of the seat to the other so as to reverse the position of the back in accordance with the direction of movement of the car, a connection is made between the back and rocker plates, so that the rocker plate is actuated to change the angular disposition of the cushion when the back is shifted. This will be understood by comparing Figs. 1 and 3.

In the present construction, the means for

operating the rocker plates comprise the crank rods 26. These rods are journaled at the car aisle ends of the seat in a suitable manner and are turned by jaw-like members 27 on the ends of links 28. These links are connected to a plate 29 secured to the back of the seat. Thus, as the seat is shifted, these links swing, and through their connection to the crank rods, the latter turn and operate against the walls of the slots 25, through which they extend. This causes the rocker plates to move one way or the other, depending upon which way the back is moved and the links swung. The path of travel of the rocker plates is controlled by the shape of the slots 19.

Assume now that the parts are in the position of Fig. 3 and it is desired to move them into the position of Fig. 1, force is applied to the back, tending to move it in the direction of the arrow of Fig. 3. The rods 13 extending through the slots 19 are held in fixed position, and by reason of the angular disposition of the slots 19, the plate will be moved as it is actuated by the crank rods in a path of travel so that the angular disposition of the cushion, which is connected to the plate, will change from that shown in Fig. 1 to that shown in Fig. 3.

Just before the limit of movement of the back is reached, the rod 13, to the right in Fig. 4, will engage with the angularly disposed wall 22 of the slot 19, in which the rod is lying; and the result will be a lifting movement imparted to the rocker plate 10 and to the cushion 10. The weight of this cushion is considerable, and this lifting movement will place a retarding or braking action on the movement of the plate. This retarding action is transmitted back through the operating rods 26 to the links 28, and thus to the car seat back, so that the back is checked in its movement at this point, and as this is very close to the limit of its movement into reverse position, it will settle finally into such position with an easy and gradual movement, eliminating the violent jolt that comes when the back reaches its final reverse position when no retardation is placed thereon.

The amount of check which is given to the seat depends wholly upon the distance which the cushion 10 is moved upward, and this depends upon the degree of angle of the angular portion 23 of the slot 19. By varying this angle, the retarding or checking movement can be increased or diminished as desired. When the seat back is moved in the reverse direction from that just described, precisely the same action will take place, except that it will be carried out by the supporting rod lying to the left in Fig. 4, engaging with the walls of the slot 19 in which it lies.

Owing to the direct connection between

the rocker plates and crank rods, these plates can be spaced away from the wall and side ends of the car to allow the proper clearance at such points, and the plates can be moved laterally upon the supporting and operating rods so as to make this clearance any desired distance. The only provision that need be made in order to shift the plates is to place the proper holes in the bottom of the seat cushion to receive the studs 24 when the rocker plates are changed.

Frequently in the repairing of cars, particularly in the painting, the workmen will remove the rocker plates for the purpose of laying planking across the supporting structure of the seat. The plates so removed will not always be replaced and are in many instances lost or mislaid. After the car has left the shop and is in condition to be again put into service, the loss of certain rocker plates is discovered and the placing of the car into service will have to be delayed awaiting the securance of rocker plates to take the place of those which have been lost in the shops. This is a source of annoyance and inconvenience to the railroads and is an objectionable feature.

In the present construction, the supporting rods pass directly through the plate and are fixedly secured to the arm of the seat and to the wall plates. Therefore, the rocker plates cannot be removed without the removal of the supporting rods, and the danger of the plates being taken off and lost is overcome.

Although the invention has been described with considerable particularity, it is not deemed to be limited other than may be by the terms of the appended claims.

40 I claim:

1. In a mechanism of the class described, the combination of a seat embodying a movable back and a cushion, a rocker plate upon which the cushion rests, a connection between the back and rocker plate, whereby when the back is moved the rocker plate is actuated to change the angle of the cushion, and means embodied in the rocker plate for retarding the movement of the back just prior to the back reaching its limit of movement, substantially as described.

2. In a mechanism of the class described, the combination of a seat embodying a movable back and a cushion, a rocker plate supporting the cushion, a connection between the back and rocker plate, whereby when the back is moved the rocker plate is actu-

ated to change the angle of the cushion, supporting rods for said plate, said plate being formed with offset slots through which said rods pass, and said rods and offset portion coöperating to retard the movement of the plate and back just prior to the back reaching its limit of movement, substantially as described.

3. In a mechanism of the class described, the combination of a seat embodying a movable back and a cushion, a rocker plate supporting the cushion, a connection between the back and rocker plate, whereby when the back is moved the rocker plate is actuated to change the angle of the cushion, supporting rods for said plate, said plate being formed with slots through which said rods pass, each of said slots comprising an elongated portion, an angular portion and a terminal portion, and said angular portion and rods coöperating to retard the movement of the plate and back just prior to the back reaching its limit of movement, substantially as described.

4. In a mechanism of the class described, the combination of a seat embodying a movable back and a cushion, a rocker plate supporting the cushion, a connection between the back and rocker plate, whereby when the back is moved the rocker plate is actuated to change the angle of the cushion, said plate having companion slots therein, supporting rods extending through said slots, a portion of the walls of each of said slots being angularly disposed with respect to the remainder of said walls, and said angularly-disposed portion engaging the rods as the plate is moved and acting to retard the movement of the plate and back just prior to the back reaching its limit of movement, substantially as described.

5. In a mechanism of the class described, the combination of a seat embodying a movable back and a cushion, a rocker plate supporting the cushion, a connection between the back and rocker plate whereby when the back is moved the rocker plate is actuated to change the angle of the cushion, fixed supporting rods engaging a surface on said plate, and said surface being formed with an offset portion with which said rods engage as the plate is moved, said engagement acting to retard the movement of the plate and back just prior to the back reaching its limit of movement, substantially as described.

SHERIDAN A. WALKER.
